UNITED STATES PATENT OFFICE.

OSCAR J. HUNGERBÜHLER AND CHARLES SCHOPPER, OF FAR ROCKAWAY AND NEW YORK, N. Y.

HAIR-WAVING DEVICE.

Application filed June 22, 1922. Serial No. 570,238.

To all whom it may concern:

Be it known that we, OSCAR J. HUNGERBÜHLER, a citizen of Switzerland, and a resident of Far Rockaway, borough of Queens, 5 in the county of Queens and State of New York, and CHARLES SCHOPPER, a citizen of Germany, and a resident of the city of New York, borough of Manhattan, in the county and State of New York, have invented a 10 new and Improved Hair-Waving Device, of which the following is a full, clear and exact description.

This invention has relation to permanent hair waving devices and has particular reference to an improvement in the construction of the core member thereof.

One of the principal objects of the present invention resides in the provision of a 20 core member for permanent hair waving devices which effects a wave of gradually increasing size from the root to the outer end of the hair in order to more closely simulate the natural wave.

As a further object the invention contemplates a device which permits of the waving of the hair closer to its root or the scalp.

As a still further object the invention contemplates a device which eliminates the necessity of tying the hair at the roots, thereby 30 eliminating the pain resulting from the tying operation and effecting a considerable saving of time in preparing the hair for the waving operation.

As a still further object the invention 35 contemplates a device which admits of an expansion of the hair after the same has been applied to the core, thus precluding the necessity of a tight initial wrapping of the same thereabout.

40 The invention furthermore contemplates a device of the character described which may be used in connection with a heater or shell member of any approved type.

With the above recited and other objects 45 in view, the invention resides in the novel construction set forth in the following specification, particularly pointed out in the appended claims and illustrated in the accompanying drawing, it being understood that the right is reserved to embodiments other than those actually illustrated herein to the full extent indicated by the general meaning of the terms in which the claims are expressed.

In the drawing—

Figure 1 is a view illustrating the core members constructed in accordance with the invention in applied position to the hair.

Fig. 2 is a side view of one of the core members removed.

Fig. 3 is a longitudinal sectional view therethrough illustrating respectively in full and dotted lines the contracted and expanded positions of the core.

Fig. 4 is an enlarged detail transverse sectional view through the core taken approximately on the line 4—4 of Fig. 2.

Referring to the drawings by characters of reference, the core comprises a stationary section 10 and a movable section 11 which is pivoted to the stationary section by a pivot pin 13. The stationary section 10 is provided at one extremity with a tubular extension 14 which is interiorly threaded as at 15 to receive the exteriorly threaded bushing 16. The opposite extremity of the section 10 is provided with a head 17 having a rearwardly projecting bill or hook 18 formed with an inclined or tapering wall 19. The juncture of the head with the bill 18 and the section 10 defines a circular transverse space 20 with which a receiving mouth 21 communicates. The sections 10 and 11 are of half oval shape in cross section and their confronting faces are provided with complementary semi-conical grooves 22 and 23 which decrease in size 75 from the pivotal connection between the sections toward their free ends. The sections 10 and 11 taper exteriorly from their 80 pivotally connected ends to their free ends and the section 11 is inclined as at 24 at its free end. A conical expansion stem 25 is disposed within the grooves 22 and 23 of the sections 10 and 11 and is threaded at one 85 extremity as at 26. The threaded extremity 26 extends through a central threaded bore 27 of the bushing 16 and is provided at its outermost end with a non-circular portion 28.

In use and operation the headed extremity 17 which may be termed the inner end of the core is engaged with a lock of hair close to the scalp by entering said lock through the mouth 21 and positioning the same within the circular transverse space 20. The lock of hair is then wound about the sections 10 and 11 of the core which

are initially contracted by retracting the conical stem 25. After the lock has been wound from the inner end toward the outer end, the outer ends of the hair are tied to 5 the stem. A key or wrench is engaged with the non-circular or squared portion 28 and the stem rotated to effect longitudinal or axial movement of the same through the core toward the inner headed end 17 thereby 10 expanding or effecting relative separation of the sections 10 and 11. This action serves to tighten the hair wrapped about the core and at the same time advance the beveled or inclined free extremity 24 of the section 11 against the inclined wall 19 of the bill 18 to lock the hair at the inner end within the transverse circular space 20. The outer shell or heater is then telescopically arranged over the core and hair in the usual 15 manner. The oval formation of the core tends to produce the true marcel wave instead of the curl or kink produced by a round core. The taper of the core from its inner to its outer end produces a larger wave at the outer ends and a smaller wave 20 at the inner end to more closely simulate the natural wave. The tapered condition in which the hair is maintained during the heating operation also tends to compensate 25 for the conical formation of the hair which is larger at its root than at its outer end. By providing a core which may be expanded after the hair is wrapped thereabout the necessity of obtaining a tight initial wrapping 30 is eliminated. The formation of the interlocking hooked retaining extremity at the inner end of the core does away with the necessity of tying the hair at the roots, thereby eliminating the pain and added 35 amount of time incident to such tying operation. When the waving operation is completed a key or wrench is again associated with the portion 28 and by retracting the conical stem 25 axially the contraction of 40 the body of the core is effected to facilitate the removal of the core from the hair. It is of course understood that if desired the 45 expanding action of the core may be done

away with and the same used in a predetermined set position.

We claim:

1. A core for permanent hair waving devices comprising a body consisting of a pair of sections of half oval shape in cross section and having pivotal connection with each other at their outer ends, said sections having complementary semi-conical grooves in their confronting faces with the restricted ends thereof disposed toward the free ends of the sections, a conical stem axially movable with respect to said sections and received in said grooves for effecting the advancement of the sections toward and away from each other, and a hooked terminal at the free end of one section adapted to be engaged by the terminal of the opposite section upon advancement of said sections away from each other to lock and maintain the hair within said hooked terminal.

2. A hair curler and waver comprising an expansible tubular member upon which the hair is adapted to be wound, means extending into said tubular member for expanding the same whereby the coils of hair are drawn taut thereupon, and interengageable means at the inner end of said member, operable upon expansion of the same for locking the hair thereto.

3. A hair curling and waving device comprising a body around which the hair is adapted to be wound, said body consisting of a pair of sections having pivotal connection at their outer ends, means extending between said sections for effecting relative separation thereof whereby the hair coiled thereabout is drawn taut upon the body, one of said sections extending beyond the other at its inner end and provided with an outwardly projecting inclined face, the free inner end of the opposite section being provided with an inclined face which upon relative separation of said sections are adapted to engage for locking the strand of hair against displacement.

OSCAR HUNGERBÜHLER.
CHARLES SCHOPPER.
